UNITED STATES PATENT OFFICE

2,525,091

GRAVE MARKER AND BASE

Edgar G. Brownawell, Gary, Ind.

Application May 25, 1948, Serial No. 28,983

1 Claim. (Cl. 40—124.5)

1

This invention relates to grave markers. It is an object of the present invention to provide a grave marker which is made of light material and can be easily transported and handled and which will have the appearance of a heavy stone and wherein the assembly is made of parts, one of which forms a base and adapted to contain cement and the other of which forms the top of the marker attachable to the top of the base.

Other objects of the present invention are to provide a light weight marker formed of metal which is of simple construction, inexpensive to manufacture, easy to assemble and fix in the ground, of pleasing appearance, durable, and long lived.

For other objects and for a better understanding of the invention, reference may be had to the following detailed description taken in connection with the accompanying drawing, in which:

Fig. 1 is a perspective view of the top part of the marker.

Fig. 2 is a fragmentary perspective view of the bottom of the top part of the marker and looking into the interior thereof and on the bottom and in full perspective upon the base of the marker, and the parts being collected but spaced from one another.

Fig. 3 is a sectional view, in elevation, of the marker.

Fig. 4 is a bottom plan view of the base.

Referring now to the figures, 10 represents a base formed of metal, preferably stainless steel which will not readily corrode, and having a top 11 with elongated hole 12 therein through which a hand may be extended and bolt holes 13. In the sides and ends of the base 10 are openings 14 and 15 through which cement 16 may be poured to fill the base.

Adapted to rest on the top of the base is a top part 17 likewise made of metal or stainless steel and which has a bottom 18 with a hand opening 19 thereon and bolt holes 21.

Before the cement 16 is poured into base 10, the base part and the top part are assembled and fixed together by bolts 22 and nuts 23. The bottom of the base 10 is opened and hands can be extended through the same and through the hand holes 12 and 19 to extend the bolts 22 through the bolt holes in the bottom of the top part and in the top of the base. The nuts 23 are tightened thereon and the top part 17 becomes rigid with the base.

Thereafter, a bottom 25 may be welded as indicated at 26 to close the base so that it may receive the cement 16. The cement 16 will be poured through the openings 14 and 15 and as soon as the same has dried, these openings can be closed with a plug as indicated at 27. The marker then may be set in the ground and the cement 16 will serve as ballast to hold the marker upright. The marker may be surrounded if necessary with cement.

2

The top part 17 may be of any desired shape or configuration. In the present form, one face has a depression therein indicated at 27' in which is fixed a name plate 28.

Preferably the bottom, as indicated in Fig. 4 at 31, is removable from grooves in the side walls of the base so that the base need not be welded at the place where the marker is to be installed. By having the bottom 31 removable, the top part 10 can be assembled upon the base 18 and thereafter the base put in place and the cement poured into the base. Accordingly, the assembly will not have to be made until parts are located at the place of installation. The base thus will not have 15 to be connected by welding.

While various changes may be made in the detail construction, it shall be understood that such changes shall be within the spirit and scope of the present invention as defined by the appended claim.

Having thus set forth and disclosed the nature of my invention, what is claimed is:

A grave marker comprising a hollow box-shaped base member having a top portion with a hand opening therein and with bolt holes spaced from the hand opening, but accessible therefrom, a hollow box-shaped top member having closed top and side portions and a bottom portion with a hand opening therein and with bolt holes spaced therefrom but accessible from the hand opening, said hollow top member bearing external indicia on one of its side portions, said hollow base member having a bottom which is removable to permit access through the base member to the hand openings in the base member and in the top member whereby the bolt holes of the respective members can be reached through the base member and without need for access through the top and side portions of the top member, bolt 30 means extended through the bolt holes of the top and base members to secure the members together, said base member having a side portion with an opening therein and through which ballast material can be passed when the bottom of 35 the base member is in place, and ballast material within the base member and lying on the base member bottom.
